UNITED STATES PATENT OFFICE.

RUDOLF PLATZ, OF ROTTWEIL, WÜRTEMBERG, GERMANY, ASSIGNOR TO
PAUL WOLF, OF NEW YORK, N. Y.

MATCH.

SPECIFICATION forming part of Letters Patent No. 275,074, dated April 3, 1883.

Application filed December 26, 1882. (No model.)

To all whom it may concern:

Be it known that I, RUDOLF PLATZ, of Rottweil, Württemberg, Germany, have invented a new and Improved Match, of which the following specification is a full, clear, and exact description.

This invention relates to an improved match which may be lighted and will glow in windy weather, and may be used for lighting cigars and for similar purposes.

The invention consists in the combination of a flat stick with a disk of tinder and with phosphorus, the tinder being fastened against one side only of the stick, all as hereinafter more fully set out.

In the accompanying drawings, Figure 1 is a perspective view of my improved match. Fig. 2 is a front view thereof; and Fig. 3, a vertical longitudinal section on line xx , Fig. 2.

All the figures are drawn on an enlarged scale.

Similar letters of reference indicate corresponding parts in all the figures.

The letter a represents the stick of a match. This stick is not of the usual form, but is considerably wider than it is thick. Near the top thereof is fastened, against one of its flatsides, a disk, b , of a suitable tinder, which will glow

when ignited. Owing to the flat shape of stick a , this stick will present a proper surface to which the tinder may be applied. The upper edge of the tinder and of the stick a , or of either, is dipped into phosphorus or equivalent substance, c . When the phosphorus is lighted by friction, the flame ignites the tinder, which will glow for a period sufficient to light a cigar. As the tinder is backed by the flat stick a , it may be pressed firmly against the cigar. Moreover, by attaching the tinder to one side of the stick a only, the danger of self-ignition of the matches in the boxes will be greatly reduced.

I do not claim to have invented a tinder on a match which surrounds the stick of the match; but

I do claim—

The combination of a flat stick, a , with the disk b of tinder, and with the phosphorus c , the tinder being fastened against one side only of the stick a , substantially as and for the purpose specified.

RUDOLF PLATZ.
